US0D1035623S

(12) United States Design Patent (10) Patent No.: US D1,035,623 S
(45) Date of Patent: * Jul. 16, 2024

(54) REMOTE CONTROL

(71) Applicant: Roku, Inc., San Jose, CA (US)

(72) Inventors: Gregory Michael Hogan, Dublin, CA (US); Paul Nangeroni, San Francisco, CA (US); Anthony John Wood, Palo Alto, CA (US); Fred Bould, Menlo Park, CA (US); Jeremy Wolf, San Francisco, CA (US)

(73) Assignee: Roku, Inc., San Jose, CA (US)

() Term: 15 Years

(21) Appl. No.: 29/892,498

(22) Filed: May 18, 2023

(74) Attorney, Agent, or Firm — Sterne, Kessler, Goldstein & Fox PLLC.

(57) CLAIM

The ornamental design for a remote control, as shown and described.

DESCRIPTION

FIG. 1 is a top perspective view of a remote control showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the remote control that form no part of the claimed design.

1 Claim, 6 Drawing Sheets
